UNITED STATES PATENT OFFICE.

DELIA F. ABRAHAMSON, OF CHICAGO, ILLINOIS.

KNEE PROTECTOR.

Application filed February 25, 1918. Serial No. 218,985.

To all whom it may concern:

Be it known that I, DELIA F. ABRAHAMSON, a citizen of the United States, and a resident of Chicago, in the county of Cook and State of Illinois, have invented certain new and useful Improvements in Knee Protectors, of which the following is a full, clear, and exact description.

The invention relates to knee protectors. 10 Soldiers in the trenches are frequently required to remain on their knees for long periods and this has been found to cause rheumatism or other diseases in the joints and sometimes abrasion of the skin or other 15 injury. This also is destructive to clothing, particularly when the ground is wet.

One object of the invention is to provide a simple protector which is adapted to be worn without discomfort under the circumstances aforesaid and which will protect the knee against moisture and abrasion and to overcome the difficulties above set forth.

The invention consists in the novel features hereinafter set forth and more particularly defined by claims at the conclusion hereof.

In the drawings: Fig. 1 is a perspective of a knee protector embodying the invention. Fig. 2 is a front view. Fig. 3 is a pattern of the waterproof covering and flannel lining. Fig. 4 is a detail of the interlining. Fig. 5 is a vertical central section of the central portion of the protector.

The entire protector is formed of thin 35 flexible material, as distinguished from a stiff or padded device, so that while it is worn it will not cause any discomfort or interfere with entire freedom of movement of the wearer. The protector comprises a piece 40 of waterproof fabric, such as thin waterproofed canvas or other thin fabric 6, a lining of flannel 7 and an interlining of flannel 8, which is disposed to extend over and furnish additional warmth and protection for the knee cap. To give the protector the desired form, so that it will fit the knee 45 comfortably, the fabric 6 and lining 7 are cut into the shape shown in Fig. 2. The side portions of the fabric 6 and lining 7 50 converge laterally from the center to the ends, and a V-shaped notch or dart 9 is cut

into each end as shown and the edges 15 of these openings are then brought together and lapped so that the protector will have the desired fullness to receive and fit around the 55 knee cap and front of the leg. The converging side or end portions will avoid any superfluous material on the sides and back of the leg, when the protector is on the person. The V-shaped notches terminate laterally of the center of the protector, so that that portion on which the leg will bear, when the wearer is kneeling, will not have any 60 seams which might hurt the wearer. The waterproof fabric and lining are secured together near their margins by seams passing therethrough on the dotted line 16 and through a tape 10 on the front face of the fabric 6, which serves as a reinforcement and prevents the seam from cutting the 70 waterproof fabric. Ordinary thin cotton tape, which is freely flexible is adapted for this purpose. To furnish additional protection over the knee and cap at the front, and without rendering the protector stiff or uncomfortable, a piece 8 of flannel, approximately the shape shown in Fig. 4, is sewed between the waterproof fabric and the flannel lining by a seam 12 which extends through the lining, but not through the 80 waterproof fabric. Tapes 14 are extended over the seams 15 of the lapped edges of the openings 9 to serve as a cover for and reinforcement of said seams and the free ends of these tapes are of sufficient length to be 85 lapped around the leg to effectively and comfortably secure the protector in place.

The invention exemplifies a protector which is particularly designed to protect a person from diseases of, and injuries to, 90 the knee and which can be comfortably worn and does not interfere with free locomotion.

The invention is not to be understood as restricted to the details set forth, since these may be modified within the scope of the 95 appended claims, without departing from the spirit and scope of the invention.

Having thus described the invention, what I claim as new and desire to secure by Letters Patent, is:

1. A knee protector comprising a piece of freely flexible waterproof fabric having con-

verging and notched sides and the margins of the notches lapped and secured together to form a central bulge and tapes for securing the protector in place overlying and secured to the joint formed by said lapped margins.

2. A knee protector comprising a strip of

flexible waterproof fabric and flexible lining and having laterally converging side-portions, an interlining sewed to said lining 10 and unattached to the waterproof fabric, and means for securing the protector around the leg.

DELIA F. ABRAHAMSON.
